UNITED STATES PATENT OFFICE.

CARL ALBERT HIRTH, OF CANNSTATT, NEAR STUTTGART, GERMANY.

FEEDING DEVICE FOR MACHINE-TOOLS AND THE LIKE.

No. 909,300.

Specification of Letters Patent.

Patented Jan. 12, 1909.

Application filed December 10, 1907. Serial No. 406,907.

To all whom it may concern:

Be it known that I, CARL ALBERT HIRTH, a subject of the German Emperor, residing at Cannstatt, near Stuttgart, Germany, have 5 invented a certain new and useful Improvement in Feeding Devices for Machine-Tools and the Like, of which the following is a specification.

This invention relates to a certain improvement connected with the feed devices 10 of machine tools and the like.

In the present feed devices for holders in machine tools it is usual to employ a screw spindle with square or taper threads, the 15 rotation of which advances or draws back a nut mounted thereon. This device is unsuitable for precision machine tools, such for instance as grinding machines in which even fractions of the hundredth part of a 20 millimeter have to be taken into consideration, because, on account of the film of oil necessarily present in the various threads it is impracticable to obtain a reliable and sufficiently precise adjustment free from all 25 backlash.

The object of the present invention is a precision feed device for holders in machine tools and the like in which a reliable adjustment and extreme accuracy are obtained by 30 employing for the adjustment of the holder slide a wheel or the like provided with incline surfaces which are brought into contact with a spring or weight-controlled holder or a lug of the same on the one side, and rest 35 against an abutment or the frame on the other, such abutment and the movable part being located substantially opposite to each other so that the interposed wheel or the like transmits the pressure of the slide or 40 holder directly to the frame and thus any possibility of bending or yielding of the wheel or the like is obviated.

In the accompanying drawings: One form 45 of the device is shown in Figure 1 which is a section of a holder, while Figs. 2 and 3 show a modification in different positions.

Referring to Fig. 1.—On the casing *a* is 50 adjustably mounted the holder slide *b* which carries a grinding spindle *c* with a grind stone *d* or some other operating part. The slide *b* is connected, by means of the rope *e*, passing over a pulley *f*, with the weight *g*, under the influence of which the lug *h* of the slide is pressed against an adjustable part 55 such as the wheel *i*. This wheel *i* is mounted in the casing *a* on a stud *k*, and is provided

on one side with an inclined surface *l*, the other side being flat and resting against an abutment *m* on the casing *a* which is situated as is seen near the rim of the wheel. The 60 wheel *i* has gear teeth *n* on its rim and is operated by a hand wheel *o* and pinion *p*.

As the adjusting wheel *i* is rotated the holder slide *b* is either pushed forward by the inclined surface *l* or forced back by the 65 weight *g*. In this way the entire pressure on the adjusting wheel is taken up by the casing, so that inaccuracies due to the bending or tilting of the wheel are precluded. Inaccuracies due to the presence of a layer 70 of oil in lubricating, are also obviated, because when suitable materials are used for the adjusting wheel and parts in contact with same, no lubrication is required.

• The sloping surface of the wheel can of 75 course be repeated more than once in the circle.

Figs. 2 and 3 show a modification of the adjusting part or wheel. In this case it is in the form of a plate, disk or wheel *t* bevelled on one side and placed on a second plate disk or wheel *s* also inclined on one surface but plane on the other. The plate or disk *t* which rests with its front inclined surface against the lug *h* of the holder, can be 80 rotated on a stud *u* of the plate or disk *s*, and held fast in any desired position by the nut *v*. The plate or disk *s* is fixed on the shaft *k* and rests with its rear or plane face against the stop *m* of the machine frame or 85 casing. The shaft can be turned from the gear *n'*. By turning the plate or disk *s*, the extent to which the holder will be moved when the shaft *k* is turned can be regulated at will. 90

In the position shown in Fig. 2, the incline on the plate or disk *t* counteracts the incline on the plate or disk *s*, and no feed motion is imparted when the shaft *k* is turned. In the position shown in Fig. 3, the inclined surfaces of the two plates or disks act in conjunction, and a half turn of the gear *n'* imparts to the lug *h* the maximum feed stroke, from *h* to the position *h'* shown in dotted lines Fig. 3. Any desired intermediate 105 stroke between *h* and the maximum stroke shown in Fig. 3, can be imparted by relatively adjusting the plates or disks.

What I claim is:—

1. In a machine of the class described, the combination of a slide, a stationary abutment, and a cam movable relative to and

bearing against both the abutment and slide, the points of contact between said cam and the slide and abutment being in the same plane, for the purpose described.

5. 2. In a machine of the class described, the combination of a slide, a stationary abutment, and a part movable relative to and bearing against both the abutment and slide, the surface of the said part that bears on the 10 slide being inclined and contacting with the slide at a point opposite its point of contact with the abutment, for the purpose described.

15. 3. In a machine of the class described, the combination of a slide having on one face a projecting lug or stud, a stationary abutment arranged in line with said lug, and a cam movable between and having its opposite faces bearing against said lug and abutment, whereby the thrust of the slide will be 20 transmitted directly to the abutment and deformation of the cam prevented.

25. 4. In a machine of the class described, the combination of a slide, a stationary abutment, a cam wheel having one surface engaging the slide near its periphery and its opposite surface engaging the abutment at the same distance from the axis of the wheel 30 as the point of contact between the latter and the slide, and means for turning the wheel.

35. 5. In a machine of the class described, the combination of a part carrying an inclined surface, means for adjusting such inclined surface on its carrying part, means for mov-

ing said carrying part, a fixed abutment for such part on one side, and a part adapted to abut against the inclined surface and to be moved by same, such fixed abutment being located substantially opposite the part to be 40 moved.

6. 6. In a machine of the class described, the combination, of a part carrying an inclined surface and a plane surface, means for moving said part, a second part also having an 45 inclined surface and a plane surface, means for adjustably securing such two parts together, a fixed abutment for the rear face of one of such parts and a part adapted to abut against the front surface of the other part 50 and to be moved by same.

7. 7. In a machine of the class described, the combination of a disk having an inclined surface and a plane surface, means for moving such disk, a second disk also having an inclined surface and a plane surface, a stud and nut for adjustably securing one disk to the other, a fixed abutment for the rear face of one of such parts, a movable holder and a part carried by such holder adapted to abut 55 against the front surface of the other part and to be moved by same.

In testimony whereof I have hereunto set my hand in the presence of two subscribing witnesses.

CARL ALBERT HIRTH.

Witnesses:

OTTO GRAF,
GUSTAV STEIN.
